GRINDER

Ralph P. Thompson, Pocomoke, Md., assignor of
one-half to William A. Scholey, Ann Arbor,
Mich.

Application October 23, 1930. Serial No. 490,611

11 Claims. (Cl. 51—55)

This invention relates to improvements in grinders, and has for its object a grinding apparatus in which the grinding table is supported in such a manner that it may be adjusted in a horizontal plane, or in any plane approximately horizontal.

It is also an object of this invention to provide in connection with a table a grinding wheel, and means for supporting the grinding wheel in such a manner that it may be moved freely over the table and at the same time be supported in substantially a condition of equilibrium.

It is a further object of this invention to provide in connection with a support member a grinding table supported either in a horizontal plane or any plane substantially horizontal, and in addition thereto an arm supported for a vertical adjustment and adapted to swing in a horizontal plane over the face of the table.

20 It is an object of my invention to provide a swinging arm pivotally mounted at a distance from a grinding table, with vertical guides nearer to the table than the pivotal bearings of the swinging arm, thereby providing means to keep 25 the center of weight of the swinging arm close up to the vertical guides to thereby reduce to a minimum the side pull on the guides.

It is a fundamental feature of my invention to provide a compound adjustment of the grinding 30 table in combination with a swinging arm.

I accomplish my object by a novel construction which renders it possible for the operator to quickly and accurately adjust the work to be ground, and to follow with an easy manual operation of grinding. The work is supported upon a table that may be tilted toward any point of the compass so that the work may be adjusted and ground at any desired angle in relation to the surface that rests upon the grinding table. A 40 swinging arm is provided that swings horizontally and carries at its free end a grinding wheel. The swinging arm is pivotally mounted in such a manner as to cause the wheel to travel in an arc across the face of the work when the arm is 45 manually operated to swing back and forth.

These and other advantages will appear from the following description taken in connection with the drawings.

50 Referring to the drawings:

Figure 1 is a view in side elevation showing the support and the vertical guides.

Figure 2 is a top plan view of the structure shown in Figure 1.

55 Figure 3 is a view similar to Figure 1 but with the intermediate table supported thereon.

Figure 4 is a top plan view of the structure shown in Figure 3.

Figure 5 is a view similar to Figures 1 and 3 showing the grinding table mounted on the intermediate table.

Figure 6 is a view of the structure shown in Figure 5 but at a right angle thereto.

Figure 7 is a view similar to Figure 1 but with the adjustable carriers mounted on the guides.

Figure 8 is a top plan view of the structure shown in Figure 7.

Figure 9 is a side elevation of the completed structure showing the adjustable table, the carriage on the guides, and the rocker arm carried by the carriage.

Figure 10 is a top plan view of the structure shown in Figure 9.

The different figures show progressively the different steps in the construction and formation of this grinder. The reference numeral 1 is used 75 to designate a support or standard which is formed of a hollow casting. Extending to one side at the upper end of this support or standard is an arm 2, which has on its outer end two vertical openings through which guides 3 extend. 80 The lower ends of these guides rest in shoes 4 and are supported in a vertical position, as clearly shown from the different figures.

On the other side of the support or standard from the arm 2 is a pair of trunnions 5 which 85 pivotally support an intermediate table 6, which has extending from one side thereof a pair of arms 7 with holes therein to receive the trunnions 5. Extending downwardly from the body part of the intermediate table is a vertical arm 8, which has extending therethrough substantially horizontally a screw member 9. The inner end of this screw member engages the standard or support, while on the outer end there is a hand wheel 10. By operating this hand wheel the position of the intermediate table 6 may be adjusted in regard to the horizontal plane.

On one end of the intermediate table is a lug 11 which extends upwardly therefrom and has on each end a trunnion 12. These trunnions are 100 at right angles to the trunnions 5 and constitute a pivotal support for a grinding table 13, which has extending downwardly therefrom at one end ears or arms 14, with holes therein to receive the trunnions 12. The other end of the grinding table 13 is supported and adjusted by means of a screw 15, which extends through the intermediate table. This screw is operated by a hand wheel 16 for the purpose of adjusting the grinding table in regard to its horizontal position.

By means of the screws 9 and 15 the grinding table 13 may be adjusted to any position from a horizontal plane to a plane not horizontal, providing the inclination of the plane be not too great from the horizontal.

5 The upper ends of the guides 3 are reduced in size and have supported thereon a head block 17, as shown in Figures 7 and 9. This head block is held in position on the upper ends of the guides by means of nuts. This head block is triangular in shape, having the guide members extending through two of the corners, while extending through the other corner is a screw member 18 the lower end of which is threaded into a carriage while on the upper end there is an operating wheel 19.

The carriage is indicated by the numeral 20 and has extending therefrom at each end an arm 21. Each of these arms has a pair of holes therethrough for receiving the guides 3. In the present instance one arm is above the arm 2 of the support member, while the other arm is beneath the arm 2. By this means the carriage is supported in a fairly firm condition in its adjustment vertically by means of the screw 18.

25 Extending from the carriage opposite the arms 21 are two other arms 22. These arms 22 are not only opposite the arms 21 but are also oppositely extending from the grinding table. In these arms 22 are holes for receiving trunnions or bearing members on a swinging arm 23. For engaging the holes in the arms 22 the swinging arm is provided with two bearing members or trunnions 24, as shown in Figure 9. One of these trunnions is on one end of the swinging arm, while the other trunnion is on a shoulder projecting from the arm adjacent the center of the swinging arm. The arm 23 is more or less U-shaped pivoted at one end to one of the arms 22, while the central part 40 is pivoted to the other arm 22.

The swinging arm extends upwardly from the lower arm 22 and over the upper arm 22 and out over the grinding table 13 so that when this arm swings the grinder supported on the end 45 of the swinging arm will move over the face of the grinding table, and in order to permit the free swinging movement of this arm the arm has not only the foregoing curved structure, as shown in Figure 9, but is also curved as shown in Figure 50 10, so that it may freely swing and not be obstructed by any of its supporting structure. In Figure 10 the grinder is shown supported immediately above the central part of the grinding table, but is shown in dotted lines with the grinding means at each end of the table. Not only are the relative positions of the grinding means shown but the relative positions of the arm 23 are shown.

On the outer end of the swinging arm 23 and 55 over the grinding table is a motor 25, which has extending therefrom the usual motor shaft. On this shaft is the grinding wheel 26 which rotates above the face of the grinding table. For the purpose of manipulating the grinding wheel and 60 swinging the swinging arm there is provided a knob 27 to be gripped by the hand of the operator. As shown in Figure 9 the table may be adjusted by operating the wheels 10 and 16. The operation of these wheels adjusts the horizontal 65 or relatively horizontal position of the table. The operation of the wheel 19 adjusts the carriage 70 vertically up and down on the guides 3. By operation of the screw 18 the grinding wheel 75 may be brought near to or removed from the grinding table. By regulating the horizontal po-

sition of the table the operator is able to determine whether the two faces of the object worked upon shall be parallel or at an angle one to the other. This angularity may be adjusted by operation of the wheels 10 and 16.

I desire to comprehend within my invention such modifications as may be embraced within my claims and the scope of my invention.

Having thus fully described my invention, what I claim is new and desire to secure by Letters Patent is:

1. In a machine for grinding in a plane, a structural member with vertical guides thereon, a carriage slidably mounted upon said guides and means for adjusting said carriage to various heights thereon, a swinging arm pivotally mounted upon said carriage and adapted to swing horizontally, a grinding spindle mounted in bearings upon said swinging arm at a distance from said pivotal bearings of said arm greater than the distance from said pivotal bearings to said vertical guides, a work table supported by said structural member, said swinging arm adapted to swing said grinding spindle in an arc across the face of said work table with the 100 lines of said vertical guides cutting a triangular plane, the triangle of said plane having a point at each end of said arc of travel of said grinding spindle and its other point coincident with the axial line of the said pivotal bearings of 105 said swinging arm.

2. In a grinding machine, a structural member and a grinding table supported thereby, vertical guides upon said structural member adjacent to said grinding table, a carriage mounted 110 upon said vertical guides, pivotal bearings upon said carriage the axial line of which parallels the said vertical guides on the side opposite thereof from the said grinding table, a swinging arm mounted to swing horizontally upon said 115 pivotal bearings of said carriage, and a grinding spindle mounted in bearings upon said swinging arm at a distance from said pivotal bearings to cause said grinding spindle to travel in an arc across the face of said grinding table, said 120 arm having a crook in the horizontal dimension thereof to cause said arm to encompass said vertical guides at one extreme of the travel of said swinging arm.

3. In a grinding machine for grinding in a 125 plane, a structural member, a grinding table supported by said structural member, an intermediate supporting member for said grinding table, said supporting member being articulated upon said structural member in such fashion as to cause it to have a tilting motion in two 130 directions from that of a horizontal plane, the said 135 articulations of said table upon said intermediate supporting member and said supporting member upon said structural member arranged at right angles to each other, a swinging arm supported by said structural member upon pivotal bearings, and a grinding spindle mounted upon the free end of said swinging arm, said swinging arm adapted to pass said grinding spindle back and forth across the face 140 of said grinding table.

4. In a grinder, a support, a table pivoted at one side to said support, a second table pivoted at one end to the first table, the pivot of the second table being at right angles to the pivot 150

- of the first table, an arm pivotally and slidably supported at one end by the support for vertical adjustment and swinging movement, and a grinder carried by the other end of the arm and 5 adapted to be moved over the tables.
5. In a grinder, a support having trunnions thereon, a table pivoted at one side to said trunnions, means engaging the other side to adjust said table on the trunnions, said table having 10 trunnions thereon at one end at right angles to the first trunnions, a second table pivoted at one end to the second trunnions, means engaging the other end of the second table to adjust it on its trunnions, and grinding means carried by the 15 support for vertical adjustment and for movement over the last-named table.
6. In a grinder, a support member, a grinding table supported thereby and adapted to be adjusted to a horizontal plane or any plane approximately horizontal, a vertical guide on said support member, a carriage on said guide, means to adjust the carriage on said guide, an arm pivoted at one end to said carriage, and a grinding means carried by the other end of said arm for travel 25 across the face of the grinding table.
7. In a grinder, a table supported for adjustment to a horizontal plane or any plane approximately horizontal, a guide member adjacent the table, a carriage on said guide member, means to 30 adjust the carriage vertically on said guide member, an arm pivoted to said carriage opposite the table, and a grinding means on said arm adapted to travel over the face of the table.
8. In a grinder, a support member having on 35 one side a grinding table, means to adjust said table to a horizontal plane or any other plane approximately horizontal, a pair of vertical guides on the side of said support opposite the table, a
- carriage on said guides opposite the support member, means to adjust the carriage vertically on the guides, an arm pivoted at one end to the side of the carriage opposite the table, said arm being curved so that its free end may pass over the 80 table, and a grinding means on the free end of the arm adapted to travel over the face of the table.
9. In a tool of the character described, a grinding table, means for providing a compound adjustment therefor, a swinging arm having on one end a grinder for movement over the table, vertical guides for said swinging arm, and means for pivotally supporting the other end of said swinging arm so that the vertical guides are between the pivotal support of the swinging arm and said grinding table.
10. In combination, a support, a grinding table adjustably mounted thereon, a pivotally mounted swinging arm having a tool on one end adapted to move over said grinding table, a guide for the other end of said swinging arm located between one end of the arm and said table whereby the center of weight of the swinging arm may be maintained relatively close to the guide, and the 100 side pull on the guide reduced to a minimum.
11. In combination, a support, a grinding table, means for effecting a compound adjustment of said grinding table with respect to said support, a vertical guide, a pivotal support thereon for a 105 swinging arm, a tool carrying swinging arm so pivoted to said support that the guide is between its pivotal support and the table, and the arm is arranged to extend from its pivotal support from a point behind the guide from the table, around 110 the guide to a point over the table.
